TOOTHBRUSH AND TOOTHPASTE KIT

Andrew J. Alboreo and Melvin W. Pratt,
Akron, Ohio

Application October 28, 1950, Serial No. 192,789

9 Claims. (Cl. 132—84)

1

This invention relates to a kit comprising a combined toothbrush and toothpaste receptacle and, in particular, to a device adapted for dispensing the toothpaste directly. The prior art contains numerous examples of single containers for both a toothbrush and toothpaste, designed for the convenience of travelers, but invariably the container has been of a rigid nature adapted merely for storing either a tooth cleaning powder or a separate tube of the collapsible type, bearing toothpaste.

According to the present invention, the receptacle, or at least the part of it intended to carry the toothpaste, is of such a nature that toothpaste may be dispensed directly from it, by collapse of the tube, with the tube reverting to its normal form upon release of the collapsing pressure. This constitutes a collapsible dispensing tube which may be refilled with paste from time to time.

It is therefore an object of the invention to provide a collapsible toothpaste holder which is readily refillable. A further object of the invention is to provide a receptacle which has sufficient normal rigidity to provide a carrying container for an object such as a toothbrush and yet which is temporarily deformable for the purpose of dispensing material such as toothpaste by pressure on the container. In still greater particular, it is an object to provide a container having dual compartments adapted, respectively, to accommodate a toothbrush and toothpaste, and the container comprising a material which is temporarily deformable to provide for dispensing of toothpaste by collapse of the tube. Another and more particular object is to provide a container according to the foregoing in which a closure member for the toothbrush compartment serves the additional function of an adaptor for refilling the toothpaste compartment.

These and other ends are attained by the invention, one preferred form of which is described in the accompanying specification and illustrated in the drawings, in which:

Fig. 1 is a view showing toothpaste being dispensed from the combination kit, onto a toothbrush.

Fig. 2 is a side elevational view of the kit,

Fig. 3 is a view in axial section of the kit of Fig. 2,

Fig. 4 is a view in partial axial section showing toothpaste being injected into the storage compartment of the kit, and

Figs. 5 and 6 are end elevational views of the kit of Fig. 2, as seen, respectively, from the left and right ends thereof.

Referring to the drawings by characters of

2

reference, there is shown a tube 10 of circular cross-section, having an open end 11 and a frustoconical end portion 12 with a restricted opening 13, and preferably beaded as at 14 to provide a flared opening and impart increased strength against rupture. A partition 16 divides the tube into respective compartments 17 and 18. Compartment 17 is intended for the storage and subsequent dispensing of toothpaste, and compartment 18 is intended to house a toothbrush 19.

End 11 of the tube is closed by a plug 20 of thermosetting plastic or the like, having a reduced portion 21, slightly tapered, for frictional fit in opening 11, and this plug has an opening 22 through which the handle 23 of the toothbrush projects when the brush is stored in compartment 18. In order to restrain the handle 23 from axial movement outwardly of the plug, the handle is provided with a rib 24 of larger diameter than opening 22.

Plug 20 also serves the additional function of an adaptor for transferring paste from a conventional toothpaste tube to the compartment 17 of the kit. For this purpose, the reduced portion 21 of the plug is internally threaded at 26 to mate with the standard thread 27 of a conventional toothpaste tube 28 (Fig. 4). Also, the outer part of plug 20 has a narrow, frusto-conical extension 29 adapted for forcing into the opening 13 of compartment 17 for forcing paste through opening 22 into the said compartment. Preferably, extension 29 will have one or more flutes 31 to provide for escape of air from compartment 17 as the paste is inserted.

After charging of compartment 17 with toothpaste, the opening is sealed by a suitable stopper. For quick action, a friction stopper such as that shown at 32 in Fig. 3 may be employed. This comprises a disc-form head 33 of sufficient diameter to afford ready grasping by the fingers and an inner, pear-shaped portion 34, adapted to readily penetrate opening 13 and lodge behind the same.

Tube 10, or at least that portion of the tube defining compartment 17, is preferably composed of a readily deformable material having elastic recovery, such that paste may be extruded from the tube without permanent deformation thereof, as is the case with conventional paste tubes. We have found that this and other purposes are served with quite satisfactory results by employing polyethylene plastic as the material of the tube. This material is tough, yet elastic, so as to be deformable to distort the tube, yet provide automatic recovery to normal form. The high permissible elongation permits enlarging of opening 13, without unduly large applied force, to re-

3

ceive stopper 32 or filler plug extension 29. Furthermore, this material is highly impermeable and resistant to corrosion. Also, it may be transparent or translucent so that the supply of paste may be observed at all times.

While polyethylene is preferred, other deformable plastics may be employed, without sacrificing the essential benefits of the invention. For example, there may be used natural or synthetic rubbers of proper stiffness, yet resistant to cracking upon repeated creasing, bearing in mind that it will be found expedient, in the effective practice of the invention, to repeatedly collapse the tube walls so that the opposite sides thereof make contact throughout a considerable length of the tube.

The tube may be made in any convenient manner. For instance, partition 16 may be molded integrally with end 17 or end 18, in which case the other end is attached by heat sealing or cementing. Or, the entire tube may be made in a molding operation and the partition then secured in place by appropriate means.

While opening 22 has been shown as circular in section, it may, of course, be rectangular in form to comport with the conventional shape of toothbrush handles, or it may be otherwise polygonal in form.

While a certain preferred form of the invention and specific details have been shown and described, it will be understood that this is mainly for purposes of illustration and that the invention is not to be deemed as limited, except insofar as shall appear from the spirit and scope of the appended claims.

What is claimed is:

1. A receptacle for isolated storing of a toothbrush and toothpaste comprising a tube, a partition in the tube defining separate compartments therein, said tube having an end opening in one compartment of a size adapted to receive a toothbrush, a closure plug for said end opening, said tube having an end opening in the other compartment of restricted size relative to the end opening in said one compartment, and the material of said tube comprising, at least in the portion defining said other compartment, polyethylene.

2. A receptacle for isolated storing of a toothbrush and toothpaste, comprising a tube, a transverse partition in the tube defining separate compartments arranged in tandem, axially of the tube, said tube having an end opening in one compartment of a size adapted to receive a toothbrush, a closure plug for said end opening having an axial passage for accommodation of a toothbrush handle, said tube having an end opening in the other compartment of restricted size relative to the end opening in said one compartment, and the material of said tube comprising polyethylene.

3. A device as in claim 2, said closure plug having a tapered spout externally of said tube, adapted for insertion in said opening of restricted size.

4. A device as in claim 2, said closure plug having an internally threaded portion internally of said tube.

5. A device as in claim 2, said closure plug having an internally threaded cavity internally of said tube, and having a tapered spout externally of said tube, adapted for insertion in said opening of restricted size.

6. A receptacle for isolated storing of a toothbrush and toothpaste comprising a tube, a par-

4

tition in the tube defining separate compartments therein, said tube having an end opening in one compartment of a size adapted to receive a toothbrush, a closure plug for said end opening, said tube having an end opening in the other compartment of restricted size relative to the end opening in said one compartment, and the material of said tube comprising, at least in the portion defining said other compartment, a plastic, deformable material having properties of full elastic recovery and resistance to cracking; said opening of restricted size having a flared mouth.

10 7. A receptacle for isolated storing of a toothbrush and toothpaste comprising a tube, a partition in the tube defining separate compartments therein, said tube having an end opening in one compartment of a size adapted to receive a toothbrush, a closure plug for said end opening, said tube having an end opening in the other compartment of restricted size relative to the end opening in said compartment, and the material of said tube comprising, at least in the portion defining said other compartment, a plastic, deformable material having properties of full elastic recovery and resistance to cracking; said opening of restricted size having a flared mouth.

15 8. A receptacle for isolated storing of a toothbrush and toothpaste comprising a tube, a partition in the tube defining separate compartments therein, said tube having an end opening in one compartment of a size adapted to receive a toothbrush, a closure plug for said end opening, said tube having an end opening in the other compartment of restricted size relative to the end opening in said compartment, and the material of said tube comprising, at least in the portion defining said other compartment, a plastic, deformable material having properties of full elastic recovery and resistance to cracking; said opening of restricted size comprising a beaded rim defining a flared mouth.

20 9. A receptacle for isolated storing of a toothbrush and toothpaste comprising a tube, a partition in the tube defining separate compartments therein, said tube having an end opening in one compartment of a size adapted to receive a toothbrush, a closure plug for said end opening, said tube having an end opening in the other compartment of restricted size relative to the end opening in said one compartment, and the material of said tube comprising, at least in the portion defining said other compartment, a plastic, deformable material having properties of full elastic recovery and resistance to cracking; said opening of restricted size comprising an external head, a neck portion adapted for lodgement in said opening of restricted size, and an internal head portion adapted to lodge behind said opening of restricted size.

25 10. A receptacle for isolated storing of a toothbrush and toothpaste, comprising separate tubular members including separate compartments joined in tandem, axially of the tube, said tube having an end opening in one compartment of a size adapted to receive a toothbrush, a closure plug for said end opening having an axial passage for accommodation of a toothbrush handle, said tube having an end opening in the other compartment of restricted size relative to the end opening in said one compartment, and the material of said tube comprising polyethylene.
